UNITED STATES PATENT OFFICE.

GUSTAVE F. FUCHS, OF BELLEVILLE, ILLINOIS.

SECTIONAL BOILER.

1,107,510.

Specification of Letters Patent. Patented Aug. 18, 1914.

Application filed February 2, 1914. Serial No. 816,117.

To all whom it may concern:

Be it known that I, GUSTAVE F. FUCHS, a citizen of the United States, residing at Belleville, in the county of St. Clair and State of Illinois, have invented certain new and useful Improvements in Sectional Boilers; and I do declare the following to be a full, clear, and exact description of the invention, such as will enable others skilled in the art to which it appertains to make and use the same.

This invention relates to improvements in sectional boilers.

One object of the invention is to provide a boiler comprising a series of hollow sections which are constructed and arranged to form when properly connected, the magazine, fire-box and the smoke and gas conducting flues and combustion chamber of the furnace, said fire-box and flues being arranged to produce the base burning and down draft features which are desirable in this form of boiler.

With this and other objects in view, the invention consists of certain novel features of construction, and the combination and arrangement of parts as will be more fully described and claimed.

In the accompanying drawings: Figure 1 is a perspective view of my improved boiler with parts broken away and in section; Fig. 2 is a central longitudinal vertical section of the boiler; Fig. 3 is a vertical cross sectional view taken through one of the sections of the boiler and on the line 3—3 of Fig. 4; Fig. 4 is a vertical longitudinal section taken on the line 4—4 of Fig. 3; Fig. 5 is a horizontal sectional view taken on the line 5—5 of Fig. 3; Fig. 6 is a similar view taken on the line 6—6 of Fig. 3; Fig. 7 is a similar view taken on the line 7—7 of Fig. 3; Fig. 8 is a vertical cross section taken between two of the sections of the boiler on the line 8—8 of Fig. 2; Fig. 9 is a similar view taken on the line 9—9 of Fig. 2 and looking at the inner side of the rear section of the boiler; Fig. 10 is an inner side view of the front section of the boiler.

My improved boiler comprises a front section 1 and a rear section 2 and a series of intermediate sections 3, 4 and 5 and 6. All of the sections of the boiler are hollow or are provided with water circulating spaces and said sections are connected or securely fastened together to form the boiler by tie rods or bolts 7 which are suitably arranged

therethrough as shown. The water spaces at the top of the sections and at the opposite sides of the bottom thereof are connected by slip joints in the form of nipples 8 which are engaged with the discharge openings on one side of the sections and with the inlet openings in the adjacent sides of the adjoining sections whereby the water is permitted to circulate freely between the hollow walls 65 of the sections.

The front section 1 of the boiler comprises a front plate 9 having arranged in the center of the upper portion thereof a firing door 10 and in the lower portion thereof a slicing door 11. In the front plate on opposite sides of the firing door are formed cleanout openings 12, similar openings 13 being arranged on opposite sides of the lower door 11, while between the upper and lower cleanout doors and in line therewith are arranged intermediate cleanout doors 14. The sides of the section 1 are in the form of hollow water legs 15 which are connected at their upper ends with an arched water chamber 80 16 which forms the top of the section. Spaced from the hollow sides or water legs 15 of the section 1 are intermediate water legs 17 which extend from the bottom of the section to a point in line with the bottom of the upper clean out openings 12 in the front plate of the section. At their lower ends the water legs 17 are connected with the lower ends of the hollow sides or outer water legs of the sections by short hollow 90 connections 18 and at their upper ends said water legs are connected with the hollow sides or outer water legs 15 by similar hollow connections 19, said connections 19, however being only approximately half the width of the water legs 15 and 17, thus forming a space or opening 20 between this part of the section 1 and the adjacent part of the adjoining section 2. Connected at their upper end to the inner sides of the chamber 16 forming the top of the section and extending downwardly therefrom parallel to the intermediate water legs 17 are inner water legs 21. The water legs 21 are spaced a short distance from the water legs 17 and terminate at their lower ends in line with the top of the space forming the firebox hereinafter described.

The section 2 of the boiler comprises hollow sides which form outer water legs 22 and which are connected at their upper ends by a hollow arched water chamber 23.

Spaced a suitable distance from the water legs 22 formed by the sides of this section are intermediate water legs 24. The legs 24 are connected at their lower ends to the 5 lower ends of the outer water legs 22 by hollow connections 25 and said water legs 24 terminate at their upper ends in line with the upper ends of the intermediate water legs 17 of the section 1. At their upper 10 ends the water legs 24 are connected with the outer water legs of the section by transverse hollow water circulating connections 26, which are of less width than the water legs 24, thus forming on one side the continuous spaces 27. Midway between the upper 15 and lower ends of the water legs 24 the latter are connected with the outer water legs by hollow connections 28, said connections being of less width than the water legs 24 and being disposed below the spaces 27 formed by the connections at the upper ends 20 of the water legs. Connected at their upper ends with the water chamber 23 and extending downwardly parallel with the intermediate water legs 24 and spaced a suitable distance therefrom are inner water legs 29 the lower ends of which terminate in line with the top of the fire-box or with the lower 25 ends of the inner water legs 21 of the section 1. The lower ends of the water legs 29 are connected to the adjacent portion of the intermediate legs 24 by hollow connections 30 on each side of which and between the same and the corresponding connections of the adjoining sections are formed draft 35 openings 31 which will be hereinafter described.

The section 4 of the boiler comprises hollow sides which form outer legs 32 and 40 which are connected at their upper ends to an arched water chamber 33. Spaced from the sides or water legs 32 are intermediate legs 34 which are connected at their lower ends to the lower ends of the outer water 45 legs by hollow connections 35 and at their upper ends are connected to the outer water legs by hollow connections 36, said connections being of less width than the water legs and disposed in positions between the 50 opposite edges of the legs as shown. Between the opposite sides of the connections 36 when thus arranged and similar connections on the adjoining sections of the boiler are formed openings 37 which provide for 55 the circulation of the products of combustion through the passages formed between the water legs as will be hereinafter described. The water legs 34 are also connected with the outer water legs 32 by hollow connections 38 corresponding to the 60 connections 28 of the section 3 except that the connections 38 extend entirely across the space between the inner and outer water legs as shown. Extending downwardly from 65 and connected at their upper ends with the

chamber 33 are inner water legs 39 which are connected at their lower ends with the intermediate water legs 34 by narrow centrally disposed hollow connections 40. The water legs 39 are also connected with the upper ends of the water legs 34 by narrow hollow connections 41 which are arranged in line with the lower connections 40.

The section 5 of the boiler is constructed in exactly the same manner as the section 4 75 except that the inner water legs 42 of this section are connected by a hollow wall 43 which extends from the top of the fire box upwardly to and is connected at its upper end with the arched water chamber of the 80 section 5. The wall 43 forms the back of the magazine above the fire-box of the boiler, the front of the magazine and fire-box being formed by the front plate of the section 1 hereinbefore described.

The section 6 of the boiler comprises hollow sides which form outer water legs 45 and which connect at their upper ends with the arched water chamber 46 of this section. Spaced from the water legs 45 and extending upwardly in parallel relation thereto are inner water legs 47 which connect at their lower ends with the lower ends of the outer water legs by hollow connections 48 and said inner water legs 47 are further 95 connected with the outer water legs above the connections 48 by hollow connections 49 corresponding to the similarly arranged connections in the sections 4 and 5. The water legs 47 terminate at their upper ends in 100 line with the intermediate water legs of the previously described section and said water legs 47 are connected at their rear edges by a hollow vertical wall 50 which extends from the bottom to the top of the boiler and 105 is connected at its upper end with the water chamber 46. In the upper portion of the hollow wall 50 immediately below the water chamber 46 and adjacent to the side edges of the wall are discharge openings 51 which 110 form an outlet for the products of combustion passing from the space 52 which is formed between the wall 43 of the section 5 and the wall 50 of the section 6 and which communicates at its lower end with the 115 space forming the fire-box, and through which the smoke and gases are drawn from the latter.

The rear section 2 of the boiler comprises hollow sides 53 which form outer water legs 120 and which are connected at their upper ends to a hollow arched chamber 54 forming the top of this section. The water legs 53 are connected at their lower ends by a hollow connection 55 which extends entirely across 125 from one side to the other of the section and forms the bottom thereof. The sides 53 are further connected above the bottom connection and in line with the intermediate connections of the previously described sec- 130

tions by a hollow transverse partition 56 which separates the rear section into an upper combustion chamber 57 and a lower smoke box or chamber 58. The hollow sides, 5 top, bottom and partition of the section 2 are connected at their rear edges with a hollow wall 59 which forms the rear end of the boiler. In the lower portion of the wall 59 and opening into the center of the 10 smoke chamber 58 is a smoke discharge opening 60 which is adapted to be connected with a stack (not shown). In the wall 59 immediately above the partition 56 and near the opposite sides of the combustion chamber 57 are clean out openings 61 which in practice are closed by suitable doors.

By constructing the various sections of the boiler as herein shown and described it will be seen that when said sections are assembled 20 the spaces formed between the outer sides or water legs and the intermediate water legs of the sections and between the transverse hollow connections of said legs will form upper and lower continuous flues 25 62 and 63 which are connected at the front end of the boiler through the opening between the front edge of the hollow connection 28 of the section 3 and the front wall of the boiler. The upper flues 62 in the opposite 30 sides of the boiler communicate at their rear ends with the combustion chamber 57 in the rear section of the boiler, while the rear ends of the lower flues 63 connect with the smoke chamber 58 in said rear section.

The spaces between the inner and intermediate water legs of the sections form draft flues 64 the forward ends of which are closed by the front wall of the boiler 40 and the rear ends of which communicate with the draft passage between back wall 43 of the magazine and the wall 50 of the section 6. The draft flues 64 communicate at their lower ends with the space forming the 45 fire-box, through the openings formed between the various hollow connections which connect the lower ends of the inner water legs with the intermediate water legs of the sections. The flues 64 are connected at their 50 upper ends, through the openings between the upper hollow connections of the inner and intermediate water legs, with upper draft flues 65 arranged above the flues 62 and communicating therewith through the 55 openings between the upper hollow connections which connect the outer and intermediate water legs of the sections.

The course of the products of combustion through the various flues of the boiler is 60 shown by arrows in Fig. 1 of the drawings and may be described as follows: The smoke and gases when leaving the fire-box pass upwardly through the space or passage between the walls 43 and 50 and pass through 65 the openings 51 into the combustion chamber

where further combustion takes place. The products of combustion from the combustion chamber pass forwardly through the upper flues 62 to the forward end of the boiler, thence into the lower flues 63 and 70 back through said lower flues into the smoke chamber 58 from whence the products of combustion pass into a suitable stack. In addition to this circulation of the products of combustion a certain amount of the latter 75 will pass upwardly through the side draft flues 64 between the inner and intermediate water legs of the sections and into the upper draft flues 65 from whence these products are discharged into the flues 62 and 80 commingle with the products passing through the latter.

Water discharging connections 66 are arranged in the upper portion of the boiler, two of said connections being preferably 85 provided, one of which is arranged in and connects with the water chamber of the section 3 and the other of which is arranged in and connects with the water chamber of the section 5. Return water connections 67 90 are also provided on opposite sides of the boiler, said connections being preferably disposed on the outer sides of the lower ends of the side walls or outer water legs of the sections 3 and 5 as shown. It will be 95 noted that the lower ends of the side walls or outer legs of the sections are increased in width or extend outwardly beyond the outer sides of the sections as shown. By arranging the water legs or hollow walls 100 of the sections as herein shown and described it will be seen that a large heating surface is provided, thus causing the water in the boiler to be quickly heated as it circulates through said hollow walls and the upper 105 water chambers of the sections.

The sections of the boiler when constructed and connected in the manner described are supported upon a hollow base 68 in the upper portion of which is arranged a grate 110 69 which forms the bottom of the fire-box and which provides beneath said grate an ash-pit through which the ashes may be removed through a suitable door 70 arranged in the end of the base as shown. The front end of the base extends upwardly at the central portion thereof and has arranged therein a door 71 which closes the opening 11 in the front end of the boiler. It will be noted that when the various sections of the boiler 115 are assembled that the clean out openings in the front wall of the front section of the boiler are in line with the various flues of the boiler and thus permit said flues to be readily cleaned when necessary.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of 5 the invention as claimed.

Having thus described my invention, what I claim is:

1. A boiler comprising front and rear end sections and a series of hollow intermediate sections each of which comprises outer, intermediate and inner hollow water legs, said inner and intermediate water legs forming the sides of the magazine and fire box of the boiler, water chambers connecting the inner and upper ends of the water legs of said sections, hollow connections arranged between said water legs to form longitudinal draft and smoke and gas conducting flues, a combustion chamber, a smoke chamber, said 10 chambers communicating with the rear ends of said flues, a hollow wall arranged in the section at the rear end of the magazine, said wall forming between itself and the wall of the adjoining section, a passage which 15 communicates at its lower end with the fire box of the boiler and at its upper end with the combustion chamber.
2. A boiler comprising hollow front and rear end sections and a series of hollow intermediate sections each of which comprise outer intermediate and inner hollow water legs, said inner and intermediate water legs forming the sides of the magazine and fire- 20
- 25

box of the boiler, water chambers connecting the upper ends of the inner and outer water 35 legs of said sections, hollow connections arranged between said water legs to form longitudinal draft and smoke and gas conducting flues, a front wall arranged on the outer side of said front end section to form 40 the front of the boiler, a hollow wall arranged on said rear end section to form the rear end of the boiler, a hollow wall connecting the inner legs of the intermediate section adjoining the rear section, said wall 45 and the end wall of the rear section forming a combustion chamber in the upper portion of said rear section, and a smoke chamber in the lower portion thereof, said chambers communicating with the rear ends of said 50 flues, a hollow wall arranged in the section at the rear end of the magazine, said wall forming between itself and the wall of the adjoining section a passage which communicates at its lower end with the fire-box of 55 the boiler and at its upper end with said combustion chamber, and clean out doors arranged in line with the ends of said flues.

In testimony whereof I have hereunto set my hand in presence of two subscribing witnesses.

GUSTAVE F. FUCHS.
